UNITED STATES PATENT OFFICE.

JOHN W. McAULIFFE, OF PELHAM, NEW YORK.

COMBINED RAZOR AND STROPPER.

1,367,159.

Specification of Letters Patent.

Patented Feb. 1, 1921.

Application filed April 16, 1920. Serial No. 374,302.

To all whom it may concern:

Be it known that I, JOHN W. McAULIFFE, a citizen of the United States, residing at town of Pelham, county of Westchester, 5 State of New York, have invented a certain new and useful Improvement in Combined Razors and Stroppers, and declare the following to be a full, clear, and exact description of the same, such as will enable others skilled in the art to which it pertains to 10 make and use the same, reference being had to the accompanying drawings, which form a part of this specification.

My invention has for its object to produce a simple and novel safety razor containing within itself a stropping device which will permit the blade to be sharpened without removing it from the razor or employing any extraneous stropping means.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is an end view of a razor arranged in accordance with my invention, the handle being broken away;

Fig. 2 is a front view of the razor, the guard and blade being shown in section; and

Fig. 3 is a section taken approximately on line 3—3 of Fig. 2.

Referring to the drawing, 1 and 2 represent the lower and upper members of a two-part casing or housing decreasing gradually in width toward the upper end which is left open. The size and shape of the casing or housing are determined by the nature of the stropping device employed. In the arrangement shown, the stropper consists of a cylindrical member, 3, having a section cut out of one side throughout the length thereof. The member 3 is fixed upon a shaft, 4, which is journaled in the end walls of the casing, the bearings being preferably divided along the plane of the joint between the upper and lower halves of the casing or housing. A combined support and guard, 5, for a blade projects forwardly from the upper edge of the front wall of the housing. The opening in the top of the housing is closed by a hood, 6, lying just behind the member 5. The hood is carried on the up-

per ends of the arms, 7 and 8, joined together at their lower ends by a cross piece, 9; the arms 7 and 8 lying at opposite ends of the housing and bearing against the inner face of the front wall of the housing. The arms are provided with longitudinal slots, 10, through which extend suitable pins or rivets, 11, fixed in the front wall of the housing. The hood may therefore be moved up and down along a path parallel with the front wall of the upper half of the housing, from the position shown in full lines in Fig. 1 to the position shown in dotted lines. The hood may be grasped between two fingers engaging it at its ends or may be moved in any other suitable or convenient manner.

Lying within the hood and extending throughout the length thereof is a rotary blade-carrier, 12, which may conveniently be journaled at its ends in the end walls of the hood. A razor blade is attached in any usual or suitable way at its back or rear edge to the carrier; the parts being so proportioned that when they occupy the position shown in full lines in Fig. 1, the blade is held in operative relation to the guard while, upon raising the hood to the position shown in dotted lines in Fig. 1, the blade may be swung back off the support and guard and bring its free edge above the open top of the housing. Thereupon, upon again lowering the hood to the position shown in full lines in Fig. 1, the blade is lowered into the housing into operative relation to the stropping device as illustrated in Fig. 3. It will of course be understood that the stropping roller is oscillated through an angle of less than 360 degrees, first stropping the blade from one side and then from the other; the blade swinging from one side to the other while its cutting edge is opposite the cavity or mutilated portion of the cylindrical stropper. The blade is held yieldingly pressed against the stropping surface by means of one or the other of two springs or groups of springs, 14, projecting inwardly from the front and rear walls of the housing near the top thereof in position to engage with the blade when it is swung in one direction or the other. If desired, a suitable pawl and ratchet device, 15, may be provided for the purpose of compelling the user to complete a turning movement of the stropping device, once started, before beginning a return movement.

It is desirable that the hood with its blade carrier be locked against displacement both when the blade is in its shaving position and when it is in its stropping position. This 5 may conveniently be accomplished by providing the cross piece, 9, of the supporting frame for the hood with a pin or stud, 16, projecting through a slot, 17, in the front wall of the housing and supporting on the 10 outer end of the pin or stud a cam dog, 18, which, when in the position shown in full lines in Fig. 1, clamps the member 9 to the front wall of the housing and, when swung outwardly parallel with the position shown 15 in dotted lines in Fig. 1, releasing the supporting frame for the blade-carrying elements and permitting the blade to be shifted from one of its two positions to the other. The locking dog may be made to serve the 20 further purpose of locking the parts together in any one of various positions of adjustment; thus permitting the cutting edge of the blade to be nicely adjusted relatively to the guard according to the nature of the 25 beard to which the razor is to be applied.

The stopper may be operated by a crank, 19, which, when not in use, may be placed within the hollow handle, 20, of the razor, the handle of the crank having on the end a 30 screw threaded button, 21, which forms a closure for the handle when the crank is housed therein.

It will thus be seen that I have produced an extremely simple and compact self-stropping 35 razor; the housing being made of two simple sections which, when fastened together by means of a few small screws, 22, also form bearings for the stropping cylinder. The blade-carrying means consisting of the carrier 40 mounted in a simple hood with its sliding frame is not only easy of construction but it is rugged and positive in its action so that a blade may be shifted from a shaving position to a stropping position and back 45 again an indefinite number of times without danger that the parts will get out of adjustment.

While I have illustrated and described with particularity only a single preferred 50 form of my invention, I do not desire to be limited to the exact structural details thus illustrated and described; but intend to cover all forms and arrangements which come within the terms employed in the definitions 55 of my invention constituting the appended claims.

I claim:

1. A safety razor comprising a housing having a guard for supporting a razor blade in shaving position, a frame slidable on the 60 housing in a direction transverse to the guard, a blade pivotally supported in the vicinity of one long edge at the upper end of said frame, said housing having an opening therein in rear of the guard, the parts being 65 so proportioned that when said frame is raised the blade may be swung either so as to pass down into the housing through said opening or into a shaving position relatively to the guard when the frame is lowered, and 70 a stropping device within the housing for stropping the blade when it hangs in the housing.

2. A safety razor comprising a housing having a long narrow open top, a guard projecting forwardly from the top of the housing, a stropping device within the housing, a hood for closing the top of the housing, a blade carrier journaled in said hood and adapted to engage with one edge of a blade 80 so as either to hold the blade in shaving relation to the guard or depending into the housing into stropping relation to the stropping device when the hood is in its closed position, and a sliding support for said hood for permitting it to be raised and lowered bodily a sufficient distance to permit the blade to be raised from and lowered into the housing. 85

3. A safety razor comprising a holder having a guard, a carrier for a razor blade 90 adapted to hold the blade in operative relation to the guard, a movable support for said carrier, and means for locking said support in any one of a plurality of adjustable positions. 95

4. A safety razor comprising a two-part housing joined together along a transverse plane, a stropping roller arranged within the housing and journaled between the two parts thereof, the housing being open at the top, a guard projecting laterally from the top of the housing, a hood closing the open top of the housing, a blade hung at one end in said hood so as either to lie in operative relation to the guard or depend into the housing into 105 operative relation to the stropping device when the hood is in its closed position, and means for shifting the hood to permit the blade to be moved into and out of the housing. 110

In testimony whereof, I sign this specification.

JOHN W. McAULIFFE.
